UNITED STATES PATENT OFFICE

GEORGE H. BRADY, OF BALTIMORE, MARYLAND, ASSIGNOR TO IMPROVED FIRE DETECTOR CORPORATION, OF BALTIMORE, MARYLAND

WIRE CONNECTER

Application filed March 26, 1929. Serial No. 350,025.

This invention relates to an improved wire connector or binding post for connecting electric conducting wires to terminals of electric circuits and the like, and one object of the invention is to provide a novel and improved construction and organization of binding screw, washer and nut, whereby the ends of one or more conductor wires may be held firmly and securely against any possibility of casual slippage of the wire or loosening of any of the parts of the conductor.

A further object of the invention is to provide, in a connector of the character described, a resilient washer of novel construction and having a novel binding action when placed under compression, and which automatically increases the binding action on the wire during the adjustment of the clamping nut.

20 The invention consists of the features of construction, combination and arrangement of parts, hereinafter fully described and claimed, reference being had to the accompanying drawings, in which:—

25 Fig. 1 is a perspective view showing a connector or binding post of the character described embodying my invention.

Fig. 2 is a sectional view through the backing and terminal plate of the connector, showing the looped end of the wire after being engaged by the clamping nut and before the nut is fully screwed up.

Fig. 3 is a view similar to Fig. 2 showing the nut fully screwed up and the wire clamped 35 in position and the washer diametrically stressed and placed under tension.

Figs. 4 and 5 are plan views of the parts as shown in Fig. 2, illustrating the end of the wire looped in opposite directions.

40 Fig. 6 is a view similar to Fig. 2 showing a slight modification.

In the drawings is shown a support or backing plate 1 of electric insulating material, on one side of which is placed a terminal plate 2 of either conducting or non-conduct-

ing material, said backing and terminal plates being united by the improved connector or binding post, which serves also for the connection of one or more conductor wires 3 with the parts 1 and 2 and associated elements of 50 an electric circuit or the like.

The parts 1 and 2 are provided with registering openings for the passage of the binding screw 4, which is provided at one end, on that side of the plate 1 opposite that on which the terminal plate 2 is located, with a head 5, between which and the plate 1 is disposed a washer 6 of conducting metal, and between which head 5 and washer 6, or between which washer and the plate 1, may be disposed the 55 end of a conductor to which the wire or wires 3 are to be electrically connected by the binding post. It is to be understood, of course, that the washer 6 may be omitted or that it may form a terminal of a conductor to be 60 electrically coupled with the conductor or conductors 3 by the binding post.

The opposite end of the screw 4 is threaded to receive a nut 7 having an outer milled portion 8 and adapted for coaction with a resilient washer 9 disposed between the same and the outer surface of the terminal plate 2.

The nut 7 and washer 9 are of special construction in order to secure a firm clamping engagement of the end of the circuit conductor 3 therewith. As shown, each washer comprises a conical body 10, the top wall of which is provided with a conical socket member or portion 11 depending within the body 10 concentric therewith and having at its apex an 75 opening 12 for the passage of the binding post, and the nut 7 has a projecting portion 13 which is of circular form and of less diameter than the top of the socket 11 and adapted to enter the same.

In applying a wire 3, the end of the wire is looped as at 14 and engaged with the binding post and the nut then threaded in position to engage the looped end of the wire. As the nut is threaded on the binding post, its portion 13 forces the looped end of 80 85 90 95

the wire down into the socket 11, which crowds it into the binding contact between the same and the nut, and the pressure of the nut on the conical washer diametrically stresses said washer so as to put it under tension, with the result that the washer securely grips the binding post, the wire and the binding nut, thereby tightly uniting the parts against any possibility of relative movement or until the nut is forcibly reversely turned to relieve the binding action. Preferably the open, contracted end of the socket member 11 and free marginal bottom edge of the body 10 are normally arranged in the same plane.

The portions 10 and 11 of the washer are preferably beveled or slightly rounded at their point of connection and the member 11, instead of being of true conical form or tapering uniformly toward its open end, is preferably provided at an intermediate point with a slightly concaved portion or recess 11', to increase its resiliency and binding action and to adapt it to more firmly and securely hold the end or ends 14 of a conductor wire or wires 3. The binding portion 8 of the nut may be of any cross-sectional shape and of either uniform dimensions as shown by the portion 13, or it may be tapered, as shown at 13' in Fig. 6 for a firmer wedging action, it being essential only that the free end or face of said binding portion cooperating with the washer be of such diameter or transverse dimensions as to enter the flaring end of the conical socket.

Figs. 2, 3, 4 and 5 show the connector as employed for fastening the looped end 14 of a conductor 3 in position, from which it will be understood that the wire loop 14 is arranged to encompass the screw 4 between the washer and nut, after which the nut is screwed up to bind the parts together. Fig. 2 shows the first part of the binding action, in which the nut has been partly screwed up and the loop 14 has been forced into the conical socket 11 and lies within the enlarged outer end of the socket, which the binding portion 13 of the nut is about to enter. Fig. 3 shows the nut fully screwed up, and the wire looped end 14 clamped in position, from which it will be seen that as the nut is screwed up the wire looped end 14 will be forced down into the socket 11 and the latter placed under tension, as a result of which a three-fold binding effect will be obtained, first, that of contracting the loop 14 and binding it firmly within the socket 11; second, that of gripping the open contracted end of the socket against the plate 2 with a great binding force; and, third, that of laterally spreading the body 10 to increase the gripping area of the washer and at the same time put said body 10 under spring tension and diimetric stress and cause it to bind with great force on the plate 2, by means of which the wire end 14 will not only be clamped

against any possibility of becoming loose or disconnected, but the parts of the connector will also be so firmly coupled that it will be impossible for them to work loose even under very severe shocks, jars or vibrations. 70 Practical use with this device shows that while the nut may be very easily screwed up for the binding action, great force must be exerted to release it, so that an extremely reliable and safe type of connector is produced. 75

The form of the socket 11 is such, obviously, that when the wire loop 14 is forced downwardly thereinto, the socket is expanded and placed under compression, while the loop is not only closed and contracted about the binding screw, but is wedged downwardly in the socket and thereby placed under tension. By this means the wire is not only elastically gripped with great force, with the double effect, first, of cushioning the connection so as to allow relative axial movements of the parts to relieve the same from stresses and strains, and, second, that of maintaining the elastic binding connection in the cushioning movements, but it is immaterial in what direction the free end of the loop 14 is arranged with regard to the direction of turn-up rotation of the nut, that is to say, assuming the nut to turn up either to the right or to the left, it is immaterial whether the loop 14 be formed as a right or a left hand loop (Figs. 2 and 4 showing, for example, a left-hand loop and Figs. 3 and 5 a right-hand loop, in connection with a nut turning up to the right), as the forcing of the loop 14 down into the socket 11 will effect a closing of the loop even though the looped end be disposed in such position that normally the rotation of the nut would tend to move the looped end outward and expand the loop. With this construction of washer and nut, therefore, no precise care is necessary in disposing the looped end of the wire about the binding screw for the clamping action. It will further be noted by reference to Fig. 3 that the portion of the conductor 3 immediately adjacent the loop 14 will be accommodated in an increased space between the portions of the washer and nut between which such part of the conductor lies, as the washer at this point will be so diametrically stressed as to be expanded to an increased degree to accommodate the wire. The provision of the socket 11 with the concaved portion 11' increases the binding effect when the socket is placed under tension and provides a keeper to still more firmly and securely hold the wire. 115

From the foregoing description, taken in connection with the drawings, the construction and mode of use of my improved connector will be readily understood and its advantages appreciated, and it will be seen that a type of connector is provided which may be manufactured and sold at a comparative- 130

ly low cost, and which may be used for all purposes where a connector of this kind is commonly employed and it is desired to hold a conducting wire in an absolutely safe and 5 secure manner. While the construction of washer and nut disclosed is preferred, it is to be understood that the washer itself may be sold for use as an independent article of manufacture, as it may be employed in connection with a binding screw and a nut of 10 different form from that shown for binding purposes to produce a better binding effect than is possible with corresponding parts of the constructions heretofore in use.

15 Having thus fully described my invention, I claim:—

1. A wire connector comprising a binding screw, a resilient washer having an outer expandable and contractible wall and an inner 20 expandable and contractible wall, through which latter said screw extends, and a nut for engagement with the screw and for clamping a conductor within and against the said inner wall.

25 2. A wire connector comprising a binding screw, a resilient washer having a frusto conical inner socket member through which the screw extends and an outer frusto-conical flange member surrounding the socket member and connected with the flaring end of the 30 socket member and flaring in the direction of the contracted end of said socket member, and a nut for engagement with the screw and clamping a conductor within and against the walls of said socket member.

35 3. A wire connector comprising a binding screw, a resilient washer having a frusto conical inner socket member and a frusto-conical outer flange member, said socket member having its wall formed with a concavity, and a nut for engagement with the screw and for clamping a conductor within and against the walls of said socket member.

40 4. A wire connector comprising a binding screw, a resilient washer having an outer expandable and contractible frusto-conical member and an inner expandable and contractible frusto-conical member through which the screw extends, and a nut engaging the screw 45 and having a binding surface of less diameter than the enlarged end of the inner member and adapted to enter the same to force a conductor down into and against the walls of said member.

55 5. A resilient washer for connectors of the character described comprising an inner frusto conical socket member open at each end and an outer conical flange member coextensive in depth with and surrounding said socket member and having its contracted end connected with the flaring end of the socket member and flaring in the direction toward the contracted end of the socket.

60 6. A resilient washer for connectors of the character described comprising an inner

frusto conical socket member, and an outer conical flange member coextensive in depth with and surrounding said socket member and having its contracted end connected with the flaring end of the socket member and flaring in the direction toward the contracted end of the socket member, the walls of the socket being formed with a concavity.

In testimony whereof I affix my signature.

GEORGE H. BRADY.
